UNITED STATES PATENT OFFICE.

GEORGE P. FOSTER, OF NORTH ABINGTON, MASSACHUSETTS.

ANTISKID DEVICE.

Application filed November 16, 1925. Serial No. 69,350.

This invention relates to anti-skid devices and has for one of its objects the production of an inexpensive device which may be easily installed upon the wheel of a motor car, and particularly the wheel of a Ford car.

Another object is the production of such a device in which several independent loops of chain extend over the shoe, these loops being held upon the wheel by devices from 10 which the loops may readily disengage themselves when parted by wear or other means.

These objects are attained by the mechanism illustrated in the accompanying drawings.

For the purpose of illustrating the invention, one preferred form thereof is illustrated in the drawings, this form having been found to give satisfactory and reliable results, although it is to be understood that 20 the various instrumentalities of which the invention consists can be variously arranged and organized, and the invention is not limited to the precise arrangement and organization of these instrumentalities as herein shown and described except as required by the scope of the appended claims.

Of the drawings:

Figure 1 represents an elevation of a wheel having mounted thereon an anti-skid device embodying the principles of the present invention.

Figure 2 represents a section on line 2, 2 on Fig. 1, drawn to an enlarged scale, and

Figure 3 represents a section on line 3, 3 on Fig. 1, also drawn to an enlarged scale.

Similar characters indicate like parts throughout the several figures of the drawings.

In the drawings 10 represents a hub of a 40 wheel having radiating therefrom a plurality of spokes 11 on the ends of which is mounted a felloe 12.

On the felloe 12 is mounted a clincher rim 13 having a plurality of lugs 14 extending 45 downwardly therefrom and contacting with the front face of the felloe 12.

Through the felloe 12 and the lugs 14 extend bolts 15 having heads 16 on one end and nuts 17 on the opposite end.

The rim 13 is adapted to hold upon the 50 wheel the usual shoe 18.

Each bolt 15 not only extends through the felloe 12 and one of the lugs 14, but also extends through plates 19, one on the rear face 55 of the felloe and one on the front face, these plates being bent at 20 to bridge the lugs 14

while the remaining portions of each plate bear rigidly against the face of the felloe.

In the bent portion 20 of the rear plate 19 is interposed a washer 21 of the same 60 thickness as the lugs 14 so that the plates 19 are interchangeable.

These plates 19 are made in the form of segments of a circle as indicated in Fig. 1, and the opposite ends thereof have outwardly and downwardly extending ears 22 struck therefrom.

The plates 19 have also struck therefrom yielding tongues 23, the free ends of which 70 engage with the ears 22.

These ears 22 extend through loops of chain 24, each loop being continuous and portions thereof passing over the shoe 18 in parallelism, as indicated in Fig. 1.

Each loop 24 is entirely independent of 75 the other loops forming the anti-skid device and in case a loop becomes worn to such an extent that it breaks, a few turns of the wheel will cause the loop to become disengaged from the ears 22 and drop to the 80 ground. This obviates the striking of chains against the mudguard of the car, which often occurs in anti-skid devices made of chains which are now in common use.

When a loop becomes unserviceable it may 85 be removed from the ears 22 and other loops placed in commission.

Should the tire become punctured so that it is necessary to replace it, and it becomes necessary to remove the rim 13, from the 90 felloe 12, the nuts 17 are unscrewed from the bolts 15 and the plates 19 are removed from the bolts and thrown over to the rear of the wheel to permit the rim 13 to be drawn 95 off the felloe while a new shoe is being mounted thereon.

When the new shoe is installed upon the rim, this rim may be again placed upon the felloe 12, the plates 19 brought to the front 100 of the wheel and inserted on the bolts 15 after which the nuts 17 are again screwed thereon retaining both the rim and the plates 19 in position.

Any movement of the plates 19 about the axis of the bolts 15 is prevented owing to the 105 upper portions of these plates 19 bearing against the projecting portions of the rim 13.

Should it be desired to use the car without the anti-skid chains thereon, the various loops may, if desired, be removed from 110 the ears 22, leaving the plates 19 on the felloe. If it is desired, the plates may also be

removed, leaving the wheel in its normal condition.

This anti-skid device is particularly adapted for use in connection with the wheels of 5 Ford cars, but obviously it could be adapted for use on wheels of other cars.

It makes a very simple means for preventing the skidding of cars which may be readily installed at a minimum cost, the plates 10 19 being struck from sheet spring metal, the ears and tongues being struck up from the same at a single operation by suitable machines.

It is believed that the operation and many 15 advantages of the invention will be understood without further description.

Having thus described my invention, I claim—

1. In an anti-skid device for a wheel provided with a shoe held thereon by a rim having lugs extending toward the axis of the wheel; headed bolts extending through the 20 felloes of the wheel and said lugs for retaining said rim in position; a nut on one end of each bolt; metal plates secured to the 25 opposite faces of the felloe by said bolts and nuts and each having at its opposite ends ears projecting outwardly therefrom; and endless chain forming loops extending over and beyond the tread surface of the shoe and positioned by the opposite ends of said loops passing beneath said ears.

2. In an anti-skid device for a wheel provided with a shoe held thereon by a rim having lugs extending toward the axis of the 30 wheel; headed bolts extending through the felloes of the wheel and said lugs for retaining said rim in position; a nut on one end of each bolt; metal plates secured to the opposite faces of the felloe by said bolts and nuts and each having an ear projecting outwardly therefrom; and endless chains forming loops extending over and beyond the surface of the shoe and positioned by the 35 opposite ends of said loops passing beneath said ears.

Signed by me at 746 Old South Bldg., Boston, Mass., this 12th day of November, 1925.

GEORGE P. FOSTER.
